UNITED STATES PATENT OFFICE.

FLOYD OTTO GRAPP, OF REDWOOD FALLS, MINNESOTA.

SPRING MATTRESS.

Application filed October 19, 1922. Serial No. 595,558.

To all whom it may concern:

Be it known that I, FLOYD OTTO GRAPP, a citizen of the United States, residing at Redwood Falls, in the county of Redwood 5 and State of Minnesota, have invented certain new and useful Improvements in Spring Mattresses; and I do hereby declare the following to be a full, clear, and exact description of the invention, such as will enable others skilled in the art to which it 10 pertains to make and use the same.

My invention has for its object to provide an extremely simple and highly efficient spring mattress adapted to be used in various 15 different ways as a substitute for the felted or padded mattresses now in general use, and which spring mattress will be much more flexible and will more readily adapt itself to the form of the person lying there- 20 on than any of the mattresses now in general use.

The spring mattress may be used in an uncovered condition or it may be encased in a padded covering, thereby forming what 25 is generally designated as an inter-spring mattress. Preferably, however, the spring mattress, when not encased, will be covered with a thick flexible pad or very thin felted pad covering. While the improved spring mat- 30 tress may be supported in many different ways, it will preferably be placed directly on an ordinary fabric bed spring, such as in general commercial use.

This improved spring mattress has various 35 important novel features and characteristics as will hereinafter appear in connection with the description of the drawings forming part of this application.

Referring to the drawings, wherein like 40 characters indicate like parts throughout the several views:

Fig. 1 is a plan view of the improved mattress, some of the parts being diagrammatically shown and some being omitted but 45 the general outline of the mattress being indicated by dotted lines;

Fig. 2 is a bottom plan view showing a portion of the mattress, the springs being diagrammatically illustrated;

Fig. 3 is a perspective looking downward 50 on a group of interconnected springs of the mattress;

Fig. 4 is a perspective looking at the sides of a group of interconnected springs;

Fig. 5 is a perspective of one of the 55 mattress springs;

Fig. 6 shows fragments of two of the springs and a metallic link connecting the bases of said springs;

Fig. 7 is a perspective showing on an enlarged or exaggerated scale a portion of the covered wire from which the springs are made;

Fig. 8 is a transverse section on the line 8—8 of Fig. 7;

Fig. 9 is a bottom plan view showing a portion of a flexible pad adapted to be used on top of the spring mattress;

Fig. 10 is a perspective showing one of the several clips used to anchor the pad of Fig. 9 to the mattress springs;

Fig. 11 shows two interconnected mattress springs in side elevation and the applied pad in vertical section;

Fig. 12 is a view corresponding to Fig. 11, but showing the mattress springs encased within a padded casing to constitute an inter-spring mattress; and

Fig. 13 is a diagrammatic view illustrating the manner in which this improved spring mattress may be rolled.

The construction illustrated in Figs. 1 to 8, inclusive, will first be described.

The springs which make up the body of the mattress may take various different forms but, preferably, they are of the form best illustrated in Figs. 4 and 5, by reference to which it will be noted that said springs are coiled or helical springs 14 of increasing diameter toward their tops. In this preferred arrangement, the convolutions of the adjacent springs 14 are interlaced, except at the bottom turns, and the said bottom turns of adjacent springs are tangentially and directly connected by metallic clips 15 bent around the closely contacting portions and connecting the base of the spring mattress in such manner that the springs cannot shift laterally or become displaced, but permitting, nevertheless, the bases of the springs to move sufficiently to adjust themselves to movements of a bed spring on which the mattress is placed or to permit the spring mattress to be rolled up, as indicated by dotted lines in Fig. 13. Also, the bases of some of the springs that are quite widely separated may be and preferably are connected in a similar manner by long clips or links 16. These links 16 not only space the springs but keep the springs from being tilted and caught in the coils of a bed spring or in an underlying pad or fabric where the

latter is used. At this point, it is important to note that while the bases of the springs cannot slip and overlap each other, the interlaced tops of the springs may, nevertheless, be forced further together than shown in the drawings and overlapped to such an extent that rolling of the mattress into the form shown in Fig. 13 may be easily accomplished. Moreover, the spring mattress may be rolled, as shown in Fig. 3, either on the transverse or longitudinal axis of the mattress. Furthermore, by reference particularly to Figs. 3 and 4, it will be observed that, normally, the upper portions of the spring coils are so interlapped that there is clearance between the interlapping portions. This permits any spring or a group of springs to be depressed without pulling laterally on springs that are not depressed. Otherwise stated, this free interlacing or interlapping of the springs permits the upper spring portion of the mattress to adapt itself to the body of a person lying thereon, without pulling laterally the upper surface of the spring mattress out of normal shape. Moreover, by reference to Figs. 3 and 4, it will be noted that the upper ends of the spring coils are alternated or relatively set in different positions so as to bring the spring ends as far as possible from the points of interlacing of the springs.

By reference to Figs. 1 and 2, it will be noted that in one direction, the alternative rows of springs are continuously connected and the intermediate rows of springs are spaced and connected by the links 16. Otherwise stated, in the said intermediate rows, alternate springs are omitted and the links 16 are applied to span the gaps where the springs are omitted.

Of course, the above described arrangement may be varied, but, as shown, certain springs are omitted in the longitudinal margins of the mattress and the gaps there formed are spanned by links 16^a which, in turn, are connected to the adjacent springs of the intermediate rows by short links 16^b.

In a spring mattress of this character, it is, of course, evident that some of the springs will be subject to very much greater weight than others; for instance, the springs that support the body from the hips up will have to take the heaviest load and those that support the legs will be subjected to very much less load. Hence, as an important feature, I graduate or vary the tension or strength of the springs and place the springs of different tension or strength in different zones. For example, see Fig. 1, the springs in the upper rectangular zone marked A will have the greatest strength, the springs in the lower zone marked B will have the least strength, and the springs in the intermediate zone marked C will have a strength somewhere between that of the springs in the zones A and B.

Springs having their metallic surfaces arranged for frictional contact have been found very objectionable because of the noise and squeak that will be produced every time a spring is moved. This objectionable feature I have obviated by the use of springs encased or covered with a flexible sound-absorbing coating or jacket 14^a. preferably a woven fabric saturated with a hardening and lubricating material, such as paraffin, 75 The paraffin applied to fabric not only acts as a lubricant to reduce friction, but very greatly increases the solidity and wearing quality of the fabric jacket 14^a. It may be here further noted that with the springs 80 freely interlaced as illustrated and described, there is never any severe frictional contact between the coils of the spring, nor, in any case, any direct pull of the one spring on the other. The whole spring mass is so 85 flexible that it will yield and conform to the body and thereby perform all of the functions of an extremely soft and flexible mattress and, at the same time, has such resilience that it will always come back to 90 its normal shape when relieved from the load.

In Figs. 9, 10 and 11, I have illustrated a flexible pad or covering for the spring mattress. This pad 17 is preferably a tufted hair, kapok or cotton pad which is not only flexible but capable of slight stretching action. At its edges and on its under side, the pad 17 is provided with hook-ended metal clips 18 stitched or otherwise attached 100 and adapted to be hooked over the upper convolutions of the outer edge mattress springs, to thereby detachably hold said pad in position on the spring mattress. This attaching means enables the pad to be readily 105 detached when desired.

In Fig. 12, the spring mattress is shown as encased within a surrounding tufted hair, kapok or cotton casing 19, thereby forming what is generally known as an 110 inter-spring mattress.

While this improved spring mattress is advisably used on an ordinary commercial bed spring, it may, nevertheless, be otherwise used and the principles of construction 115 involved and claimed may be used in an upholstering cushion, all of which uses would be within the scope of the term "mattress" as herein used.

By reference first to Fig. 2 and then to 120 Fig. 1, it will be noted that the enlarged upper portions of the inter-connected springs form a less open or more nearly complete bearing surface, because of their overlapping, than do the lower portions of 125 said springs. This feature is also illustrated in Fig. 4.

What I claim is:

1. A spring mattress made up of coiled springs of increasing diameter toward their 130

- upper ends, their lower ends being tangentially connected and their upper portions being loosely interlaced and capable of free shifting movements, and whereby the upper portions of the spring mattress is given a great flexibility and adjustability to objects supported thereon, and the base of the spring structure is rigidly connected against lateral movements. 20
- 5 2. A spring mattress made up of coiled springs of increasing diameter toward their upper ends, their lower ends being in direct contact and rigidly connected and their upper portions being loosely interlaced and capable of free shifting movements and whereby the upper portions of the spring
- is given a great flexibility and adjustability to objects supported thereon, and the base of the spring structure is rigidly connected against lateral movements. 25
- 10 3. A spring mattress made up of connected springs arranged in one direction in alternate continuous and intermediate interrupted rows, the said continuous and interrupted rows forming rectangular groups of connected springs and the rows of rectangular groups of springs thus formed being staggered in respect to each other. 30
- 15 In testimony whereof I affix my signature.

FLOYD OTTO GRAPP.
